UNITED STATES PATENT OFFICE.

ARCH B. TAYLOR, OF CHARLOTTE, CORNELIA TAYLOR LONG, OF WINSTON-SALEM, NORTH CAROLINA, AND ARCHIE C. SOHN, OF PITTSBURGH, PENNSYLVANIA, AS-SIGNORS TO TAYLOR-LONG COMPANY, OF CHARLOTTE, NORTH CAROLINA, A CORPORATION OF NORTH CAROLINA.

DESIGN FOR A BOTTLE.

Application filed February 18, 1927. Serial No. 20,810. Term of patent 14 years.

To all whom it may concern:

Be it known that we, ARCH B. TAYLOR, a citizen of the United States, residing at Charlotte, in the county of Mecklenburg, State of North Carolina, CORNELIA TAYLOR LONG, a citizen of the United States, residing at Winston-Salem, in the county of Forsyth, State of North Carolina, and ARCHIE C. SOHN, a citizen of the United States, residing at Pittsburgh, in the county of Allegheny, State of Pennsylvania, have invented a new, original, and ornamental Design for a Bottle, of which the following is a specification, reference being had to the accompanying drawing, forming a part thereof.

The figure is a side elevation of a bottle, showing our design, both sides of the bottle being similar.

We claim:

The ornamental design for a bottle as shown.

In testimony that we claim the foregoing as our own we have signed our names to this specification.

ARCH B. TAYLOR.
CORNELIA TAYLOR LONG.
ARCHIE C. SOHN.
